UNITED STATES PATENT OFFICE.

THEODORE W. WIDENMANN AND MARCUS R. HARRIS, OF DETROIT, MICHIGAN, ASSIGNORS TO PRINTING REGISTER CO., OF DETROIT, MICHIGAN, A CORPORATION OF MICHIGAN.

ROLLER MOUNTING FOR AUTOGRAPHIC REGISTERS.

Application filed July 6, 1925. Serial No. 41,542.

This invention relates to roller mountings for autographic registers and the object of the invention is to provide a roller and mounting therefor for pressing a strip of paper into contact with the type on a type roll or cylinder.

Another object of the invention is to provide a roller mounting in which the roller may be easily turned up out of the way to allow a strip of paper from a paper roll to be threaded through an autographic register.

Another object of the invention is to provide a means whereby the roller when turned up out of the way is held in the position placed and may be easily turned down again to the operative position, a tension being placed on the roller to move it into contact with the paper strip and type roll when in the operative position.

A further object of the invention is to provide a roll supporting mechanism which may be first turned to relieve the tension on the roll after which the roll may be turned up onto the supporting mechanism in order to allow free access to the paper strip and roll.

These objects and the several novel features of the invention are hereinafter more fully described and claimed and the preferred form of construction by which these objects are attained is shown in the accompanying drawings in which—

Fig. 1 is a side elevation of a portion of an autographic register embodying my invention.

Fig. 2 is a front elevation thereof.

Fig. 3 is a view showing the roller in the raised position.

Fig. 4 is a similar view showing the roller being moved to the set position.

Fig. 5 is an enlarged section taken on line 5—5 of Fig. 1.

As shown in Fig. 1 a base 1 is provided for the autographic register and a horizontal bracket 2 is adapted to be supported on the base 1. Another horizontal bracket 3 is adapted to be supported from the base

1 and is provided with a depending end 4 forming a bearing for the type roller 5. 50 The roller 5 is provided with a type face and an inking roller 6 is rotatably mounted in the bracket 7 and is provided with a spring 8 for holding the ink rollers in contact with the type roller. A stud shaft 9 55 is secured in the horizontal bracket 2 and a paper roll 10 is rotatably mounted on the stud shaft 9. The member 11 is a paper roll tension device described in a separate application and adapted to place a slight 60 tension on the paper roll 10 to prevent the paper roll 10 from freely rotating on the stud shaft 9. The bracket 3 is provided with a notch 12 in which the shaft 13 of a roller 14 extends there being a bracket 3 65 and notch 12 at each end of the shaft 13. As shown in Fig. 3 the shaft 13 is rotatably mounted in a block 15 which is slidable in the slot 16 in the member 17 and the member 17 is provided with a bracket 70 18 carrying an adjusting screw 19 to adjust the tension of the spring 20 for forcing the block 15 toward the outer end of the slot 16. There is a member 17 at each end of the roller 14 and these members 17 are 75 connected by a bar 21. Each member 17 is pivotally mounted at 22 on a member 23 and the two members 23 are rotatably mounted on a shaft 24 the ends of which terminate within the brackets 3. As shown in Fig. 5 80 a bracket 25 is secured to the bracket 3 and a bearing block 26 is provided with a threaded shaft 27 extending through the member 25 and secured in the member 25 by the lock nuts 28. By this arrangement the position of the shaft 24 may be varied by loosening and tightening the lock nuts 28. The member 23 is provided as shown in Fig. 3, with an arcuate slot 29 through which a screw 30 extends and this screw 30 is adjustable in the slot 31 in the member 3. The member 23 may be turned on the shaft 24 as an axis until the screw 30 engages in the end of the slot 29 and the member 23 90 is provided with an arm 32 having an inwardly extending pin 33 against which the

member 17 is adapted to rest when turned to the raised position shown in Fig. 3. To move the roller 14 into contact with the type roller 5 the members 17 are turned on the 5 pivot 22 from the position shown in Fig. 3 to that shown in Fig. 4 until the ends of the shaft 13 rest on the edges 34 of the slots 12 in the two brackets 3 provided on opposite sides of the machine. At this time 10 by turning the ends 32 of the members 23 downwardly the pivotal points 22 for the members 17 are moved forward so that the ends of the shaft 13 move into the slots 12 in the members 3 and the roller 14 is moved 15 into contact with the type roll 5. As the members 23 are turned downwardly as will be understood from Fig. 1 the pivotal point 22 is moved below a line drawn from the center of the shaft 13 to the center of the 20 shaft 24 and downward movement of the pivotal point 22 is stopped at this time by the ends of the slots 29 engaging the limit screws 30. When the mechanism has been moved to the position shown in Fig. 1 the 25 tension of the spring 20 tends to hold the parts in position and the spring 20 also allows the shaft 13 to move back longitudinally of the member 17 so that the spring 20 maintains a pressure on the roll 14 and holds 30 it in engagement with the type roll. The type roll 5 shown in Fig. 1 rotates in a counter clockwise direction and is inked by the ink roller 6 before printing the paper strip. In order to thread the paper through 35 the machine the arms 32 of the members 23 are raised to the position shown in Fig. 4 to bring the pivot points 22 above a line between the centers of the shafts 13 and 24 and the members 17 are then turned upwardly on the pivots 22 until they engage the pins 33 at which time the members 23 swing back until the pins 30 engage in the 40 ends of the slots 29 as shown in Fig. 3. At this time there is considerable clearance between the shaft 24 and the type roll 5 and the strip from the paper roll 10 may be 45 easily brought up over the roll 5 at which time by moving the mechanism back to the position shown in Fig. 1 the paper strip 50 is held in contact with the type roll 5 and rotation of the type roll prints and feeds the paper strip. By adjustment of the set screws 19 the tension of the springs 20 may 55 be varied and by means of the slots 16 the shaft 13 may be supported between the ends of the slots when the roller 14 is in contact with and type roll. By means of the screw 27 and the lock nuts 28 the shaft 24 may 60 be moved toward or away from the type roll so that the shaft 13 will be supported between the ends of the slot 16. The screw 30 may be adjusted in position in the slot 31 so that the limited throw of the members 65 23 may be varied to correspond with the different positions of the shaft 24.

From the foregoing description it becomes evident that the device is very simple and efficient in operation, will not easily get out of order, is adjustable to vary the tension of the pressure rolls, is removable for loading 70 the machine, and provides a device which accomplishes the objects described.

Having thus fully described our invention, its utility and mode of operation what we claim and desire to secure by Letters Patent 75 of the United States is—

1. A roller mounting for autographic registers comprising a pair of side frame members, a bracket on each side frame member, a bolt adjustably supported in each bracket, a shaft rotatably supported by the bolts, a member pivotally mounted on each end of the shaft, means on the frame members limiting turning of the pivoted members on the shaft, a roller supporting member pivotally mounted on each pivoted member, a roller shaft yieldably supported in the ends of the supporting member, means limiting turning movement of the supporting members on the pivoted members, a yoke connecting the two supporting members and guide means on the frame members adapted to be engaged by the roller shaft when in the operative position. 80 85 90 95

2. A roller mounting for autographic registers comprising a pair of side frame members, a bracket on each side frame member, a bolt adjustably supported in each bracket, a shaft rotatably supported by the bolts, a member pivotally mounted on each end of the shaft, a roller supporting member pivotally mounted on each pivoted member each provided with a slot in the end opposite the pivot, a roller shaft rotatably supported in the said slots and slidably therein, a spring on each supporting member adapted to move the roller shaft toward the end of the slot, means for adjusting the tension of the said springs, and guide means on the frame members adapted to be engaged by the extreme ends of the roller shaft. 100 105 110 115

3. A roller mounting for autographic registers comprising a pair of side frame members, a shaft adjustably supported on the side frame members, a member pivotally mounted on each end of the shaft, means limiting turning of the said members on the shaft, a roller supporting member pivoted on each of the pivoted members, each roller supporting member being provided with a slot in the end opposite the pivot, a roller shaft slidably mounted in the said slots and yieldable means tending to force the roller shaft toward the end of the slots in the roller supporting members, each frame member being provided with a slot through which the extreme end of the roller shaft extends when in the operative position. 120 125 130

4. A roller mounting for autographic registers comprising a pair of side frame

members, a member pivotally supported from each side frame member, means limiting turning of the said members on their pivots, a roller shaft, a pair of members supporting the roller shaft, the roller shaft being movable longitudinally of the supporting members, the supporting members being pivotally mounted on the aforesaid

pivoted members, means limiting turning of the supporting members on the pivoted members, and guide means on the frame members for the roller shaft.

In testimony whereof we sign this specification.

THEODORE W. WIDENMANN.
MARCUS R. HARRIS.
